Edward Larson

By his Attorney,

Edgar Gate & Co.

UNITED STATES PATENT OFFICE.

EDWARD LARSON, OF HARTFORD, CONNECTICUT.

SPRING-COUNTERBALANCE DEVICE FOR WINDOW-SASHES.

1,235,702.

Specification of Letters Patent. Patented Aug. 7, 1917.

Application filed March 30, 1917. Serial No. 158,488.

To all whom it may concern:

Be it known that I, EDWARD LARSON, a citizen of the United States, and residing at Hartford, in the county of Hartford and State of Connecticut, have invented certain new and useful Improvements in Spring-Counterbalance Devices for Window-Sashes, of which the following is a specification, such as will enable those skilled in the art to 10 which it appertains to make and use the same.

This invention relates to spring counterbalance devices for window sashes, and the object thereof is to provide improved devices of this class whereby the sashes are normally balanced without the use of weights, and whereby said sashes may be raised and lowered and maintained in any desired position and both sashes closed whenever necessary, the sashes being manipulated by hand.

The invention is fully disclosed in the following specification, of which the accompanying drawings form a part, in which the 15 separate parts of my improvement are designated by suitable reference characters in each of the views, and in which:

Figure 1 is a plan view of the window frame provided with my improved spring counter-balanced devices;

Fig. 2 an inside sectional view of the top portion of the window frame showing the sashes and my improvement, the sashes being in a closed position;

Fig. 3 a sectional plan view of one end portion of the construction shown in Fig. 1 on an enlarged scale and showing the parts in a different position;

Fig. 4 a section on the line 4—4 of Fig. 3; and,

Fig. 5 a section on the line 5—5 of Fig. 4.

In the drawing forming part of this specification, I have shown a window frame, or that part thereof in which the sashes are 45 mounted, and said frame, as shown, comprises two similar vertical side members *a* and a horizontal top member *b*, and mounted in said frame are the usual top sash *c* and bottom sash *d*.

The top frame member is extended at both sides of the frame as shown at *b*², and the side members *a* are mortised into the top

frame member as shown at *a*² and, in the practice of my invention, I mount on the opposite end portions of the top frame member *b* spring drum attachments *e*, comprising base plates *e*² on the outer end portions of which are mounted spring drums *e*³, on each of which is wound a metal strap *f*.

The base plates *e*² of the spring drum attachments *e* are also provided adjacent to their inner ends with transverse reinforcing strips *e*⁴ which are riveted thereto, and each of which is provided with, or formed into, yoke-shaped bearings or supports *e*⁵ in which are mounted pulleys *e*⁶, and the spring drum attachments *e* are secured to the top member *b* of the window frame, in the construction shown, by bolts *g* at their front ends, and by headed screws or similar devices *g*² at their outer ends under which the base plates *e*² are slipped, but my invention is not limited to any particular means for securing the spring drum devices *e* to the top member *b* of the window frame.

The said spring drum devices *e* are also provided with web or spider frames *h* in which the spring drums *e*³ are mounted and which serve as additional bearings or supports for the central spindles *e*⁷ of said spring drums, and the spindles *e*⁷ are provided with sleeves *e*⁸ integral with, or secured to, the base plates *e*², and the springs *e*⁹ of said drums are secured to said sleeves and to the drum casings at each end, as clearly shown in Figs. 3 and 4.

The metal straps *f* are provided at their free ends with pulleys *i*, and passed around said pulleys are cords *j* and these cords, or the separate parts thereof, are passed over the pulleys *e*⁶ of the spring drum devices *e*, and down through holes *k* in the top plate or member *b* of the window frame, and also in the base plate *e*² of the spring drum devices *e*, and one end portion *j*² of one of the cords *j* is secured to the bottom sash and the other end portion *j*³ to the top sash at one side of the window or window frame, while the ends *j*² and *j*³ of the other cord *j* are correspondingly secured to the bottom and top sashes at the opposite side of the window. The connection of the ends *j*² of these cords with the bottom sash are shown at *m* in Fig. 2, and it will be understood that

the end portions j^3 of said cords, one of which is shown in Fig. 5, will be connected with the top sash in the same manner.

The position of the parts shown in Figs. 5 1 and 2 is their normal position with both sashes closed, and if the bottom sash be raised, the pulleys i will move in opposite directions toward the spring drum devices e^3 with which they are connected by the 10 straps f , and if it is desired to lower the top sash with the bottom sash open, said top sash is moved downwardly and the pulleys i again move in opposite directions, but in a direction the reverse of that first given, 15 and from the foregoing description and the construction shown, it will be apparent that both sashes may be manipulated in any desired manner, either for opening or closing the same, and it will be understood that the 20 strength or capacity of the spring drums e^3 may be so regulated as to permit of the raising and lowering of the sashes by a slight exertion, or application of power by hand, in the manner of raising and lowering sashes 25 counter-balanced by weights, and said sashes, or the counter-balancing devices may be so regulated as to permit the sashes to stand at any desired point of adjustment, or to remain in a closed position and, if desired, 30 suitable locking devices may be applied to the sashes for holding them in any desired position of adjustment, and for locking them in a closed position.

It will also be understood that the strength 35 of the spring drums e^3 may be adjusted or regulated to window sashes of any weight, and my invention is not limited to any particular form or construction of spring drum or drums, nor to any particular means of or 40 for mounting the pulleys e^6 in connection with or in proximity to said drums, and the spring drum devices e may be constructed or formed in any desired manner, and cords or cables may be substituted for the straps f , 45 and changes in and modifications of these and other features of construction herein described may be made, within the scope of the appended claims without departing from the spirit of my invention or sacrificing its ad- 50 vantages.

The top plate or member b of the window frame is provided, adjacent to each of the spring drum attachments e , with removable panels n forming pockets or apertures n^2 55 through which the spring drum attachments e may be inserted or passed and, in the construction shown, the panels n are held in place by screws n^3 which engage the ends of said panels and the corresponding ends of 60 the pockets or apertures, and the said pockets or apertures are designed to permit of and to facilitate the mounting of the spring drum devices e in which operation said de-

vices are passed through the pockets or apertures n^2 and slid outwardly into position, 65 in which operation the outer end portions of the base plates e^2 engage the headed screws or devices g^2 , after which the bolts g are passed upwardly through the top portion of the window frame and through the inner 70 end portions of the plate e^2 , and nuts g^3 are applied to said bolts for securing the spring drum devices in position, and it will be understood that, if at any time, the spring drum devices e should need repair they may 75 be taken out by reversing the above operation.

It will be understood that the form of the yoke-shaped bearings or supports e^6 in which the pulleys e^6 are mounted facilitates the operation of the apparatus and prevents the same from getting out of order by reason of the fact that the said bearings or supports are closed at the top and the cords or cables j cannot jump out of said bearings or supports, or become detached therefrom in any way.

The accompanying drawings show all the parts of the sash counter-balancing apparatus herein described exposed, but all of said 90 parts when in use will be inclosed and concealed by the other parts of the window frame not herein shown and described, and the description of mounting the counter-balancing devices herein described pertains 95 to complete window frames, as will be readily understood. If it is desired to place my improved sash counter-balancing apparatus in position, in the first instance, or while the window frames are being formed 100 or constructed, the method of procedure would, of course, be different, and the pockets or apertures n^2 would be of no use in this operation.

Having fully described my invention, what 105 I claim as new and desire to secure by Letters Patent, is:—

1. The herein described means for counter-balancing window sashes comprising spring drum devices adapted to be mounted in the 110 top portion of the window frame, flexible devices connected with and wound on said spring drum devices, pulleys connected with said flexible devices, other pulleys mounted in connection with the spring drum devices and 115 other flexible devices adapted to be passed around the first named pulleys and over the last named pulleys and downwardly and to be connected with the window sashes.

2. The combination with a window frame, 120 of sash counter-balancing devices comprising spring drums mounted in the top portion of the window frame, flexible devices connected with and wound on said spring drums, pulleys connected with said flexible 125 devices, other pulleys mounted in connection

with or adjacent to the spring drums, and other flexible devices connected with the first named pulleys and passed over the last named pulleys and downwardly and connected with the window sashes, substantially as shown and described.

In testimony that I claim the foregoing as

my invention I have signed my name in presence of the subscribing witnesses this 26th day of March, 1917.

EDWARD LARSON.
